UNITED STATES PATENT OFFICE.

ROBERT L. WARD, OF ROBINSON, ILLINOIS.

TRUSS.

1,109,379.

Specification of Letters Patent.

Patented Sept. 1, 1914.

Application filed August 14, 1913. Serial No. 784,773.

To all whom it may concern:

Be it known that I, ROBERT L. WARD, a citizen of the United States, residing at Robinson, in the county of Crawford, State of Illinois, have invented certain new and useful Improvements in Trusses; and I do hereby declare the following to be a full, clear, and exact description of the invention, such as will enable others skilled in the art to which it appertains to make and use the same.

This invention relates to trusses and particularly to pads and pad supports therefor.

The object of the invention resides in the provision of a truss which may be worn with entire comfort by the patient and in which the pad will automatically seek its proper position no matter what movements the patient may indulge in.

20 A further object of the invention resides in the provision of a truss pad and support therefor which will be simple in construction, efficient in use and which may be manufactured at comparatively small cost.

25 With the above and other objects in view the invention consists in the details of construction and in the arrangement and combination of parts to be hereinafter more fully described and particularly pointed out 30 in the appended claim.

35 In describing the invention in detail reference will be had to the accompanying drawings wherein like characters of reference denote corresponding parts in the several views, and in which—

Figure 1 is a front elevation of a fragment of a truss embodying the improved pad and pad support; Fig. 2, a section on the line 2—2 of Fig. 1; Fig. 3, a detail perspective view of the pad supporting plate detached from the belt and the pad removed therefrom; and Fig. 4, a detail perspective view of the pad detached.

40 Referring to the drawings the invention is shown as comprising a pad supporting member comprising a dished oval plate 10 which has mounted thereon in any suitable manner an eye member 11 projecting on the convex side of said plate and through 45 which is adapted to be engaged a truss belt 12. It will be noted that the opening in the eye member 11 extends transversely

of the long axis of the plate 10. Mounted upon the plate 10 at one end of the eye member 11 is a spring hook 13 which also 55 projects on the convex side of the plate. Mounted upon the plate 10 at the end of the eye member 11 opposite the hook 13 is a pair of hooks 14 the bills of which project on the concave side of the plate 10. 60

The pad is indicated generally at A and is shown as comprising a pair of substantially oval pieces of fabric 15 and 16 stitched together along their edges and filled during the operation of stitching with a suitable 65 quantity of small shot 17. Mounted upon the pad A adjacent one end thereof are eye members 17' which are engaged over the bills of the hooks 14. Secured to each side of the pad A at corresponding points are 70 flexible strands 18 and 19 which are adapted to be engaged beneath the hook 13 from opposite sides of the latter respectively.

By this construction it will be apparent that the pad can be supported so as to move 75 relatively to the plate 10 and automatically position itself in a proper manner in the cavity of the body no matter what type of movement the wearer may indulge in. It will also be apparent that the extent of 80 movement of the pad relatively to the plate 10 may be controlled by adjusting the strands 18 and 19.

What is claimed is:—

85 A truss pad structure comprising a dished plate provided with means for detachable connection to a truss belt, a hook mounted on said plate at one end thereof and projecting on the convex side of the plate, a pair of hooks mounted on the other end of 90 said plate and projecting on the concave side thereof, a pad, a pair of eyes mounted on the pad and engaged over the hooks projecting on the concave side of the plate, and flexible strands secured to opposite sides 95 of the pad and engaged beneath the hook projecting on the concave side of the plate.

In testimony whereof, I affix my signature, in the presence of two witnesses.

ROBERT L. WARD.
